CLAIM

The ornamental design for a container for fly fishing tackle, as shown and described.

DESCRIPTION

FIG. 1 is a perspective view of a container for fly fishing tackle showing my new design;

FIG. 2 is a front elevational view of the container for fly fishing tackle illustrated in FIG. 1;

FIG. 3 is a left-side elevational view of the container for fly fishing tackle illustrated in FIGS. 1 and 2;

FIG. 4 is a right-side elevational view of the container for fly fishing tackle illustrated in FIGS. 1-3;

FIG. 5 is a rear elevational view of the container for fly fishing tackle illustrated in FIGS. 1-4.

FIG. 6 is a top plan view of the container for fly fishing tackle illustrated in FIGS. 1-5; and,

FIG. 7 is a bottom plan view of the container for fly fishing tackle illustrated in FIGS. 1-6.

The detail shown in broken lines is for illustrative purposes only and forms no part of the claimed design.

The broken lines just inside the edge or trim of the front and back shell are directed to environment. The remaining broken lines define boundary, within which no claim is made.
